John H. Curtis

ATTORNEY

UNITED STATES PATENT OFFICE.

HAROLD Y. PRENDERGAST, OF NEW YORK, N. Y.

SOUND-BOX.

1,338,395.

Specification of Letters Patent. Patented Apr. 27, 1920.

Application filed June 18, 1917. Serial No. 175,273.

To all whom it may concern:

Be it known that I, HAROLD Y. PRENDERGAST, a subject of the King of Great Britain, residing at New York city, in the 5 county of New York and State of New York, have invented new and useful Improvements in Sound-Boxes, of which the following is a specification.

My invention relates to sound boxes for 10 talking machines, and its objects are to enhance the volume of sound to improve the quality and clarity of tone, to concentrate the sound vibrations at the sound egress of the box and to effect their more direct 15 transference to the sound arm, to render the stylus bar more flexible and resilient and more responsive to gradations of tone, to prevent the diversion and dissipation of any part of the sound, and in general to 20 simplify and render more effective the operation of the several parts and their accessibility to observation and repair.

My invention primarily consists in the interposition of a sounding board between 25 the diaphragm and the sound outlet of the box, whereby the quality and clarity of the tonal production is greatly improved.

My invention further consists in effecting 30 a practical separation of the stylus bar from any portion of the box except where two resilient prongs with annular grooves form a yielding attachment thereto, air spaces being provided at all other portions 35 adjacent to the bar in order to effect free play of the same and to prevent, so far as possible, any distribution of sound.

My invention further consists in providing 40 a direct passage for the conveyance of sounds from that point of the diaphragm where they are most intense, and also to prevent undesired sound waves from leaving the box and interfering with the sounds conveyed to the ear of the listener through the sound arm.

My invention further consists in effecting 45 a concentration of the sounds at or near the egress passage from the sound box, and to insure their proper transference to the sound arm.

My invention further consists in the various 50 other modifications and improvements hereinafter more specifically described and claimed.

Attention is hereby directed to the drawing 55 in which similar numerals of designa-

tion refer to similar parts throughout the several views.

Figure 1 is a view of my improved sound box looking at the same through the transparent closure. 60

Fig. 2 is a section of the same on line 2—2 of Fig. 1, looking in the direction of the arrows.

Fig. 3 is a view of my improved sound box looking at the same at the side opposite to that shown in Fig. 1, with the closure 30 removed. 65

Fig. 4 is a view of the stylus bar.

Fig. 5 is a section of the stylus bar shown in Fig. 4 looking in the direction of the 70 arrow, and

Fig. 6 is a view of a portion of the stylus bar illustrating one of the prongs.

Referring to the drawing:

Within the sound box 7 which is preferably cylindrical in shape and of metal or any other suitable material, I install the sounding board 8, the periphery of which rests upon the annular seat 9. 75

The sounding board 8 is preferably composed of wood of the character usually employed for musical instruments, but may be made of any suitable material. I prefer to use silver-grained spruce, properly seasoned and varnished in the manner that the same 80 is ordinarily prepared and used in violins or like instruments. In the center of said sounding board 8 is the circular orifice 10 through which passes the sound coming from the diaphragm 11, and which is located opposite the zone of its greatest vibration a washer 12 serving to separate the sounding board and diaphragm and to provide the chamber 13 between the same. By 85 the provision of such chamber I have found that the tone of the instrument is greatly improved, both as to quality and distinctness, the sounding board serving to increase 90 the resonance of the sound and to mellow its tone, thereby giving a very characteristic 95 effect. 100

While as used in my invention, the diaphragm 11 may be of mica or other suitable material, I prefer to use other material than mica such for instance as an opaque 105 diaphragm of fiber composition, which may be colored red or blue, or other distinctive color, and which is susceptible of being printed with the name of the maker or trade mark or embellished in some charac- 110

teristic manner; a feature which at the present time is not possessed by mica because of its brittleness and non-absorptive qualities.

- 5 For the purpose of holding the diaphragm securely in position, I provide the rubber gasket 14 bent in the form of a circle and compressed by the metallic ring 15 secured to the wall of the box by means of 10 the screws 16. At the center of the diaphragm is affixed one end of the stylus bar 20 in the usual manner. The outer end of the stylus bar is provided with the arms 21 and 22, which extend at right angles to the 15 main portion of the bar and which bear thereon the resilient rods or prongs 23 and 24, which extend in the same direction as the main portion of the bar.

- In order properly to support the said 20 stylus bar, I provide the supporting plate 25 secured to the periphery of the sounding box adjacent thereto and having slots therein registering with the prongs 23 and 24, which are secured therein by the screws 23^a 25 and 24^a coming in contact with recesses 36 near the ends of said prongs. In order to prevent any further contact of the stylus bar with other portions of the box than as above described, I provide the slot 26, which 30 extends through the said supporting plate 25 and the wall and ring adjacent thereto, thereby permitting free play of the said bar within the box and preventing diversion of vibration. As will be observed, the arms 35 21 and 22 are entirely separated from contact with the supporting plate 25 except through the prongs 23 and 24. Furthermore, for the purpose of giving greater resiliency to the bar 20 I also provide the said 40 prongs with the annular grooves 35, which are adjacent to the arms 21 and 22.

- As will be observed, the prongs 23 and 24 extend in a direction which is parallel to the portion of the stylus bar within the 45 box, and while being firmly secured to the plate 25, nevertheless, largely by reason of the exposed grooves 35 impart considerable resiliency to the stylus bar, thereby rendering the same completely responsive 50 to the movements of the stylus in a manner heretofore unknown in the art. Preferably the said prongs are of sufficient stiffness as not to be resilient except as so rendered by reason of the grooves 35. As is obvious 55 by my new construction, I dispense entirely with the hinge, pivotal, jam nut connections heretofore usually employed in prior operative structures to secure the stylus bar to the sound box, and thereby obviate any 60 sounds produced in the movement of such connections. Also by having the attachment of two prongs grooved as aforesaid and equidistant from the axis of the bar, greater steadiness and balance are imparted 65 to the same.

The outer end of the stylus bar is furnished with the usual socket 27 and retaining screw 28, provided for the reception of the stylus 29 and operating in the usual manner.

At one side of the sound box, I provide the detachable cover 30; the periphery of which is attached to the sound box by means of the screws 31 and the center of which is provided with the walled passage 32, arranged to connect with the sound arm (not shown) in the usual manner. If desired, the cover 30 may be made integral with the wall of the sound box and thereby dispense with the screws 31.

In order to insure the proper conduction of sounds through the orifice 10 of the sounding board 8, which are gathered from the chamber 13, I provide the cover 30 with the annular recess 33, within which is seated the rubber gasket 34, engaging with the surface of the sounding board in close proximity with the orifice 10. By such arrangement it is to be noticed that all vibrations of sound collected from said chamber 13 are 90 concentrated at and conducted through the orifice 10, and the walled passage 32.

As will be understood, the screws 16 pass through openings in both the wall of the box and the ring 15. Since the normal diameter of the ring is smaller than that of the bore of the box, such diameter may be increased by tightening of the screws 16, in which event the wall of the ring 15 is drawn closer to the wall of the box, and may even 100 come in contact with it. Where the ring touches the wall of the box, it is obviously at its greatest diameter and such diameter may be reduced by loosening the screws 16, in which event the ring 15 will spring away 105 from the wall of the box. Consequently, the ring 15 may, by means of the screws 16, be adjusted to various diameters and thereby affect the loose or tight engagement with the groove 17 as may be desired.

In order that the sounding board be kept in proper shape and condition, particularly when made of wood, I prefer to employ the cleats 37 which extend across the grain of the wood and are firmly secured thereto in 115 any suitable manner, such cleats, however, I do not regard as absolutely essential to the operation of such sounding board.

While I have described my invention with particular reference to its embodiment in 120 the preferred form of construction above set forth, I do not desire to be understood as confining the scope of my invention to the details of construction herein set forth, since, as is obvious, various modifications 125 and changes may be effected without departing from the spirit thereof.

What I claim and desire to secure by Letters Patent is:

1. A sound box embodying a casing hav-

- ing a sound outlet, a diaphragm and sounding board positioned within the casing in spaced relation to one another and supported therein at their outer peripheries to provide 35
- 5 an intermediate sound chamber, said sounding board being provided at its center with an aperture located opposite the zone of greatest amplitude of vibration of the diaphragm, and in alignment with the sound 40
- 10 outlet of the casing, and an annular yieldable member, of substantially the same interior diameter as the aperture in the sounding board, clamped between the sounding board and the wall of the sound box to provide 45
- 15 a continuous passage from the sound chamber to the outlet of the sound box, all parts of said sounding board, except its periphery, being free to vibrate. 50
2. A sound box embodying a casing, a 55
- 20 diaphragm and a sounding board peripherally secured within said casing and spaced apart to provide an intermediate sound chamber, the sounding board being provided with a central aperture, and the casing being similarly provided with an aligned sound outlet, and a resilient flexible and yieldable connection from the aperture in the sounding board to the outlet of the sound box to provide a continuous passage from the sound chamber out of the casing, said connection being in the form of a resilient ring having an inner diameter substantially equal to the diameter of the aperture of the sounding board, said ring being seated in the recess in the wall of the casing to maintain it co-axial with the aperture in the sounding board and clamped between the sounding board and the casing.
